UNITED STATES PATENT OFFICE.

WILLIAM M. BRUCE, JR., OF SPRINGFIELD, OHIO, ASSIGNOR, BY MESNE ASSIGNMENTS, TO THE AMERICAN AUTOMATIC TELEPHONE COMPANY, OF ROCHESTER, NEW YORK, A CORPORATION OF NEW YORK.

LOCK-OUT DEVICE FOR PARTY-LINE TELEPHONES.

972,329.

Specification of Letters Patent. Patented Oct. 11, 1910.

Application filed July 9, 1906. Serial No. 325,910.

To all whom it may concern:

Be it known that I, WILLIAM M. BRUCE, Jr., a citizen of the United States, residing at Springfield, in the county of Clark and State of Ohio, have invented certain new and useful Improvements in Lock-Out Devices for Party-Line Telephones, of which the following is a specification.

My invention relates to improvements in lock-out systems for party-line telephones, and particularly to devices and systems adapted to be used with party-line common battery exchanges.

The object of the invention is to simplify the circuits and constructions of lock-out devices of this character, and to render them capable of a more extended use without the necessity of fine adjustment.

Generally speaking, the system includes a relay at the subscriber's station which is adapted when the telephone is removed from the hook to be bridged across the line, and by its operation to switch into the circuit the subscriber's talking outfit, the construction being such that the talking instruments and the said relay will utilize the current flowing on the line so that the relay at another station would not be operated so long as the telephone hook or main operating switch at one subscriber's station is in operative position.

In devices of this character, it has been found that where the stations are placed at long distances apart the line resistance is such that a more or less fine adjustment of the relay is necessary, depending upon the location of the stations in relation to the exchange, as where one station is close to the exchange and one a long distance therefrom the difference in the line resistance will cause the relays to work with more or less efficiency, so that an adjustment to its location on the line is necessary. It has also been the practice where it is desired to connect two subscribers on the same line to employ a condenser through which the talking currents of one subscriber might pass while the battery currents are held back, thus permitting a second relay to operate on the same line.

By the improvement herein described, I obviate the necessity of a fine adjustment for the different locations on the line, and also obviate the use of the condenser to es-

tablish connections between subscribers on 55 the same line.

The invention consists in the system and means hereinafter described and pointed out in the claims.

In the accompanying drawings, Figure 1 60 is a diagrammatic view showing a common battery exchange and two subscribers' stations. Fig. 2 is a diagrammatic view of one subscriber's station showing a modification 65 of a part of the device.

In said drawings, A represents a common battery located at the exchange, and B and C subscribers' stations.

D and D' are opposite sides of the line which connect the several subscribers (any 70 number of which may be connected) to the exchange.

a is the ordinary telephone hook or switch adapted to be operated when the receiver is removed.

b is the receiver, c the transmitter and d the induction coil, which parts constitute the usual subscriber's talking outfit.

e represents a relay which is adapted to be bridged across the line by the operation 80 of the main telephone switch when the receiver is removed therefrom through the circuit 1, 1, 1, 1. The magnetic coil of this relay is constructed in two parts, e² e³, normally in series and representing preferably 85 about sixteen hundred ohms, one part being preferably of about one thousand ohms resistance, and the other six hundred ohms resistance. When the telephone is bridged across the line the sixteen hundred ohms of 90 this relay are in circuit through the circuit 1, 1, 1, 1 above mentioned. This very high resistance produces a relay that will operate on any reasonable length of line, but by reason of its high resistance it has not the magnetic 95 pull of a relay of lower resistance. I, therefore, provide means for cutting out a part of this resistance as soon as the relay operates, which it does immediately upon the closing of the circuit 1 at the main switch, 100 a, as follows:

The magnetic influence in the relay produced by current passing through sixteen hundred ohms operates the switch e¹, which establishes two circuits one of which passes from the circuit 1, through the 105 switch, e¹, and through circuit 2 through the subscriber's talking instruments, c and d, to the line, D¹. The other circuit passes

from the switch, e^1 , and circuit, 1, through circuit, 3, to the main part of the magnetic coil of the relay forming a short circuit around that part of the coil having the lowest resistance, and thus cutting out the lower resistance and leaving the coil at the proper resistance to furnish the necessary working power in the relay and also, in connection with the talking instrument, to use the current passing across the line to such an extent as to prevent the operation of any other subscriber.

In connection with this device, in the diagrammatic view herein shown, I have not included any ringing circuit, as any well-known ringing circuit, either selective or otherwise, may be employed in connection with the improvement herein described.

The operation as thus far described is as follows: Any subscriber being called by a proper signaling device removes his telephone from the hook, and by such removal establishes a bridge across the line through the circuit 1, and the entire resistance constituting the magnetic coil of the relay. The energizing of the magnetic coil of the relay produced by the current flowing through the same, will operate the switch, e^1 , and thus cut in the subscriber's talking outfit through the circuit, 2, and at the same time cut out the resistance of the part, e^2 , of the energizing coils of the relay and thus allow a greater amount of current to pass through said relay, firmly holding the switch, e^1 in its operative position, and at the same time utilizing the current to such an extent that the relay at no other station on the line can be operated, even though its main telephone switch should be operated by the removal of the receiver.

To provide for connecting two subscribers on the same line, I provide in the circuit, 2, a circuit breaker, f , adapted when operated to break the circuit, 2, including the talking instruments, thus cutting out the subscriber's talking outfit, without interfering with the circuit 1, through the relay, and establishing another circuit, 4, of purely local character which passes through a coil, e^4 , in proximity to the energizing coil, e^3 , of the relay, and thence through the relay switch, e^1 , and a part of circuit 2, through the induction coil, d , of the subscriber's outfit. This circuit it will be seen does not extend across the line and gets no current except such as may come by induction from the energizing coils of the relay. In this condition, the subscriber desiring to talk with another subscriber on the line, signals the exchange in the usual way and having given his call presses the button to operate the switch, f , cutting out his talking instruments from the line and establishing a local circuit through the inductive coil, e^4 , and the primary of the induction coil of his talk-

ing circuit. The coil, e^3 , of the relay remaining in the bridge across the line will receive any talking currents passing across the lines D D¹ by reason of the bridge across the same, and such alternating talking currents will induce a current in the coil, e^4 , which currents by reason of the local circuit established by the switch, e^1 , will be carried to the primary of the induction coil of the local receiver and thus permit the subscriber to hear what is said on the line, although said instruments are cut out from the bridge across the line. As soon as the connection is made with the other subscriber, which the first subscriber will know by the conversation, the switch f is released and the subscriber's outfit is again brought into circuit with the other subscriber also on the line. It will be understood in this connection that while the current on the line would not be sufficient to operate a relay at a subscriber's station when the relay and talking instruments of another subscriber are in circuit, yet after the relay is operated the current passing through the same will be sufficient to hold the relay and switch in operated position and thus maintain a circuit after the same has been established with two subscribers on the line.

In Fig. 2 I have shown a modification in which the coil, e^2 , instead of being placed about the core and thus forming a part of the energizing coil of the relay magnet is placed in series with the relay magnet but separate therefrom. In this case a coil of lower resistance will preferably be used and will act as a feeding coil to the relay coil, thus limiting the amount of current that will pass to the energizing coil in the event that the voltage should be somewhat higher by reason of less line resistance. This arrangement of the coils will materially reduce the fine adjustment required in placing the subscribers' stations at greater or less distance from the exchange, and has been found to be effective, although the preferable way is to put this feeding coil in series with the main energizing coil on the magnet itself, in which case both coils act as energizing coils when the instrument is first operated. In either case, the first or feeding coil will be cut out as soon as the switch is operated to establish the main talking circuit.

It will be seen that by the construction above described, I provide an arrangement and means by which the lock-out device will operate perfectly and with little or no adjustment and within any ordinary distance from the exchange and without reference to their relative position with the exchange, and by the use of the induction coil in proximity to the energizing coils of the relay and the local circuit through the talking outfit, I am enabled to dispense with the condenser and thus provide a system which forms a

complete lock-out against other parties on the line when ordinarily used, and at the same time by the use of the relay switch to establish a local inductive circuit which will 5 enable the subscriber to hear although his talking outfit is cut out of the line circuit, so as to permit another subscriber on the same line to be brought into the circuit by the operation of his relay.

10 In constructing the relay, I preferably wind the coils, e^2 , e^3 e^4 , upon the same spool, though they may be otherwise formed so long as the coil, e^4 , is in sufficient proximity to the energizing coil to obtain the inductive 15 influence.

Having thus described my invention, I claim:

1. In a party line telephone system, a series of subscribers' stations each having a 20 normally inoperative talking outfit, and a relay to bring said talking outfit into circuit, the relay at each subscriber's station having an inductive circuit including talking instruments independent of the line circuits, and 25 means for disconnecting said talking circuit from the line with the relay in circuit with said line, substantially as specified.

2. The combination at a subscriber's station of a disconnected talking outfit, a relay 30 to establish a circuit through said talking outfit, an inductive circuit through the relay and said talking outfit independent of the line circuit, means for breaking the line circuit through said talking outfit and at the 35 same time establishing the inductive circuit through said talking outfit independent of the line circuit.

3. In a party line telephone lockout system, a relay coil, resistance in series with 40 said relay coil, an inductive coil in proximity to said relay coil, means for cutting out

said resistance, and means for establishing a local circuit through the inductive coil for the subscriber's talking outfit, substantially as and for the purpose specified.

4. In a lockout for party line telephone system, a main switch, a relay adapted to be bridged across the line by the operation of said switch, a talking outfit adapted to be brought into circuit by the operation of the 45 relay, a circuit breaker to disconnect said talking outfit independent of said relay, and a local inductive circuit through said relay and talking outfit, and means for establishing said inductive circuit when the talking circuit is broken by said circuit breaker, as 50 specified.

5. In a lockout device, a relay, a normally open talking circuit adapted to be closed by 55 said relay, and a local inductive circuit through the talking instruments adapted to receive inductive currents from the coil of said relay, and means for opening and closing said inductive circuit, for the purpose specified.

6. In a lockout device, a relay coil, resistance in series with said relay coil, and an inductive coil in proximity to said relay coil, a switch operated by the relay to establish a talking circuit, means for cutting 60 out said resistance by the operation of the switch, and means independent of said relay for breaking said talking circuit and establishing a local circuit through the inductive coil and talking instruments, as specified. 65

In testimony whereof, I have hereunto set my hand this third day of July A. D. 1906.
